J. L. STUMP ET AL

POWER ELECTRIC SHEARS OR SCISSORS

Filed March 24, 1924

UNITED STATES PATENT OFFICE.

JOHN LOUIS STUMP AND CHARLES W. STUMP, JR., OF CUMBERLAND, MARYLAND.

POWER ELECTRIC SHEARS OR SCISSORS.

Application filed March 24, 1924. Serial No. 701,523.

To all whom it may concern:

Be it known that we, JOHN L. STUMP and CHARLES W. STUMP, Jr., citizens of the United States, residing at Cumberland, in 5 the county of Allegany and State of Maryland, have invented certain new and useful Improvements in a Power Electric Shears or Scissors, of which the following is a specification, reference being had there- 10 in to the accompanying drawings.

This invention relates to a power electric shears or scissors, and the object of the invention is the construction of a simple and efficient shears that comprises a minimum 15 number of parts, and which is very efficient in operation.

With this and other objects in view, our invention comprises certain novel combinations, constructions and arrangements of 20 parts as will be hereinafter described, illustrated in the accompanying drawings, and more particularly pointed out in the appended claims.

In the drawings:

25 Figure 1 is a top plan view of a mechanism showing the top or cover of the housing or casing removed.

Figure 2 is a sectional view, taken on line 2—2, Fig. 1, and looking in the direction 30 of the arrows, the cover being shown on the casing.

Figure 3 is a perspective view of the sliding block and the inner end of the driven shaft.

35 Referring to the drawings by numerals, 1 comprises the housing or casing and 2 is the top or cover thereof. In the forward end of the casing 1 is placed block 3, and in the casing, near the rear end, is block 4; the block 4 extends transversely of the casing and supports parts of the driving shaft 5 and the driven shaft 6.

The driven shaft 6 comprises an inner and an outer section which are connected 45 by the universal joint 7, producing practically a flexible shaft for driving the shear blades 8 and 9.

The lower blade 8 is fixedly fastened (by screws, Fig. 2) to the top of the forward 50 block 3, and the upper or pivotally mounted blade 9 is secured upon the fixed blade 8, at 10, so that the upper blade 9 can swing or pivot to accomplish the cutting action.

We employ a sliding block 11 (Figs. 2 55 and 3), which is placed upon the forward

block 3, and the forwardly-extending extension 12, of block 11, extends into a groove 13 in block 3. In the bottom of block 11 is formed a groove 14, into which extends the long rib 15, which serves to hold the 60 block 11 in an assembled position upon block 3. The block 11 is provided on its outer or rear face with a plurality of stud pins 16, on which stud pins are mounted tapering or conical-shaped rollers 17. 65 Formed in the outer face of block 11, just around the stud pins 16, is a horizontal groove 18, into which extends the inner end 19 of the inner section of the driven shaft 6. On this end 19 is placed a roller 20, 70 which roller is in the groove 18, (Figs. 2 and 3). Formed on the inner section of shaft 6, against block 11 is a pinion 21 which in this instance is preferably provided with three teeth that engage and travel over the rollers 17 on the stud pins 16. By reason of the pinion 21 travelling over the rollers 17, the inner section 75 of shaft 6 will have to raise and fall, causing the reciprocal movement of the sliding block 11. A screw 22 extends through slot 23 in blade 9, and positioned on screw 22 is roller 24. By changing the position of screw 22 upon block 11 the "stroke" of the blade 9 will be controlled; when the screw 22 is in the position shown in Fig. 2, it will have a longer swing, or "opening capacity" than if the screw were placed in threaded socket 22^a nearer to the outer or rear face of the block; the changing of the 80 position of screw 22 will be permitted owing to the length of the slot 23 (Fig. 2). We provide a pair of angle brackets 25 for guiding the bearing block 26 in its vertical movement; the block 26 is mounted upon the inner section of shaft 6, and the block is provided with the forced plug 27 which is for the purpose of forcing a lubricant, in the block, against the shaft 6. Each bracket 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

screws 29 and 33 the angle brackets 25 will be securely fastened to the casing, with the bearing block 26 working therebetween.

The driving shaft 5 is provided on its extreme inner end with the locking collar 34, and intermediate its ends with a gear 35. Gear 35 meshes with the large gear 36, which gear 36 is idle upon the outer section of the driven shaft 6. A friction clutch 37 is suitably keyed upon shaft 6, preferably by reason of the shaft being flattened where it is engaged by clutch 37. The clutch 37 is pressed inwardly by coil spring 38, which spring 38 is held in place by a set collar 39. Operating lever 40 is pivotally mounted, at 41, and is provided with an integral collar 42 that surrounds a portion of the clutch 37, whereby, when the operator operates the outwardly-extending portion 43 of the lever, the clutch 37 can be moved away from the gear 36 to stop the mechanism from operating while power is being supplied to the driving shaft 5 for rotating the same. When no manual pressure is being exerted upon lever 40 then spring 38 causes the clutch 37 to normally engage, in frictional contact, the gear 36 sufficient to impart rotary movement to the driven shaft while the driving shaft is rotating, and hence in this manner the shear blade 9 is operated.

A felt washer 44 (Fig. 2) is placed between block 3, block 11, the rear end of blade 8 and blade 9 to prevent any grease or lubricant moving forward to the cutting edges of the blades 8 and 9.

While we have described the preferred embodiment of our invention, and have illustrated the same in the accompanying drawings, certain minor changes or alterations may appear to one skilled in the art to which this invention relates, during the extensive manufacture of the same and we, therefore, reserve the right to make such alterations or changes as shall fairly fall within the scope of the appended claims.

What we claim is:

1. A power clipper comprising a casing, a stationary block in the forward end portion of said casing having its rear end portion shaped to provide a seat undercut at its forward edge, an upstanding rib extending transversely across the seat and in-

termidate its forward and rear edges, a stationary blade secured to said block and extending through a slot in the forward end of the casing above the block, a movable block resting in said seat and having a lip extending into the undercut forward portion of the seat, a groove being provided in the lower face of the movable block and containing said rib to guide the sliding movement of the movable block transversely of the stationary block, a movable blade pivoted upon the stationary blade and having its rear end portion extending over the movable block and having a longitudinally extending slot, a pin carried by said movable block and extending through said slot for imparting swinging movement to the movable blade when the movable block is moved in its seat, and means for imparting sliding movement to the movable block transversely of the stationary block.

2. A power clipper comprising a casing, a stationary block in the forward end portion of said casing, a stationary blade carried by said block, a movable blade pivotally mounted upon said stationary blade, a movable block slidably carried by said stationary block for movement transversely thereof and having an operative connection with said movable blade, said movable block having a pocket in its rear face and pins in the pocket in spaced relation to each other longitudinally of the pocket and extending out of the pocket, a driving shaft extending into the casing through the rear end thereof, a driven shaft in said casing having its forward end extending into the pocket, a gear carried by said driven shaft and engaging the outwardly protruding portions of the pins for imparting sliding movement to the movable block when the driven shaft is rotated, a U-shaped guide bracket in said casing straddling said driven shaft and having its arms curved longitudinally, a bearing block for said driven shaft slidably mounted between the arms of said driven shaft, and a universal joint connecting the driven shaft and driving shaft.

In testimony whereof we hereunto affix our signatures.

JOHN LOUIS STUMP.
CHARLES W. STUMP, JR.
